Primary Examiner—Lucy Lieberman
Attorney, Agent, or Firm—Oliff & Berridge, PLC**[57] CLAIM**

The ornamental design for container with handle, as shown and described.

DESCRIPTION

FIG. 1 is a right side elevation of a container with handle showing our new design, the left side elevation is a mirror image thereto except for the conventional screw threading on the neck.

FIG. 2 is a front view thereof;

FIG. 3 is a rear view thereof;

FIG. 4 is a top view thereof;

FIG. 5 is a bottom view thereof;

FIG. 6 is a side view of the handle of FIG. 1 without the container, the opposite side view being a mirror image;

FIG. 7 is a front view thereof;

FIG. 8 is a rear view thereof;

FIG. 9 is a top view thereof; and,

FIG. 10 is a bottom view thereof.

The handle is shown separately in FIGS. 6-10 for clarity of illustration.
